DOOR ACTUATED ROTATABLE SERVICE CABINET

William Henry Calcutt and Sydney Alfred Frank
Phelps, London, EnglandApplication November 9, 1948, Serial No. 59,164
In Great Britain April 28, 1948

2 Claims. (Cl. 232—1)

1

The present invention relates to apparatus for the reception of goods delivered to houses or other premises and has as a principal object to provide a device which enables goods to be delivered to the door in the absence of the householder and to be stored in a thiefproof and hygienic manner until removed from the container.

According to the present invention apparatus for the reception of goods delivered to houses or other premises comprises a cylindrical or like container divided by radial partitions into several compartments and rotatably mounted in the door, wall, gate or the like of the house or other premises, so that a portion of said container projects at the outside through an opening in said door or the like of the house or the like, where it is fitted with a sliding door accessible to the tradesman or other person delivering goods, means being provided whereby the tradesman or other person by merely moving said sliding door to one side causes the container to rotate so as to bring the next compartment into alignment with said opening for the reception of the goods being delivered, whereupon said sliding door can be moved backwards by said person so as to enclose the goods which he has deposited and prevent unauthorized access thereto.

The invention will now be described with reference to the accompanying drawings in which

Figure 1 shows a front elevation of an apparatus constructed in accordance with the present invention with the closure door open,

Figure 2 shows a side elevation of the apparatus shown in Figure 1 with the door closed,

Figure 3 shows a plan view of the apparatus with the door closed,

Figure 4 shows a detail of the apparatus on an enlarged scale,

Figure 5 shows a side elevation of the detail shown in Figure 4, and

Figure 6 shows on a similar scale a general front elevational view of the apparatus when mounted into a wall.

Referring to the drawings these show apparatus suitable for receiving domestic articles and mounted in a brickwork wall 1. The apparatus is carried or supported upon a frame 2 which is securely fixed into the wall. This may be done by bolts passing through to the rear of the wall (not shown) or by any other suitable fixing means. Supported between a bottom frame member 3 projecting from the main frame member 2 and an upper member 4 is a rotatable column 5 carried in suitable bearings 6 and 7 in

2

the members 3 and 4 respectively. About this column 5 there are carried four compartments 8, 9, 10 and 11 in the form of a cylindrical container each compartment being of quadrant section and 5 being open on the outer face there being only a wall 12 so as to retain goods placed in each compartment. The cylindrical container comprising the compartments is so arranged with respect to the opening that a portion of the container projects from the opening 13 formed in the frame 2. It is obvious that as the cylindrical container is rotated in an anticlockwise direction each compartment in turn is presented at the opening 13.

The opening 13 is closed by a sliding door 14 accessible to the tradesman or other person delivering goods and which is arcuate in shape and in the open position is housed within the framework in guides or grooves which are concentric with the cylindrical container. In fact the door 20 is supported by quadrant pieces 15 and 16 which are mounted for rotation about the column 5. In this way the door 14 is prevented from any possibility of fouling with the rotating compartments.

On the upper wall or roof of the cylindrical container formed by the compartments 8—11 is mounted above each compartment a catch member 17. This catch member is adapted to be engaged by a spring-loaded pawl member 18 carried upon the quadrant piece 15 supporting the upper edge of the door 14. The position of each catch member 17 is such that they are engaged by the spring pawl 18 when the door is fully closed and with a compartment correctly located behind the opening 13. The catch members 17 and the spring pawl 18 serve to effect rotation of the compartments every time the door 14 is opened after having been closed.

To ensure that the compartments can be rotated only in one direction a spring finger 19 locates itself into a non-return recess 20 secured on the base of the cylindrical container in the case of three of the compartments. In the case of the fourth compartment the recess is a positive locking recess 21 so that when the compartments have been rotated round to the point where the finger 19 engages the recess 21 the door is locked in the closed position by virtue of the fact that the door is engaged by one of the catches 17 mounted on the rotatable compartments and the rotatable compartments are themselves locked from rotation in either direction by the recess 21 engaging the spring finger 19.

When the door 14 is opened it rotates the compartments in a clockwise direction and exposes

a new compartment through the opening 13. These compartments are located correctly with respect to the opening 13 by means of a spring fork member 22 comprising a pair of levers pivoted at 23 and connected by a tension spring 24 engaging a square section 25 of the column 5. As the compartments are rotated the column 5 is also rotated and the square section 25 forces the spring fork open until the next pair of flats engage the limbs of the fork. The fork then closes upon the flat faces and so locates each of the four compartments accurately behind the opening 13.

An audible warning is also incorporated into the mechanism shown in the drawings, this warning comprising a normal electric bell (not shown) which bell has the circuit completed by means of a cam member 26 secured to the quadrant piece 15 supporting the door bearing upon a contact 27 which on passage of the cam 26 beneath it is elevated to make contact with a second contact member 28 to complete the bell circuit in a normal manner. This bell operates twice on operation of the apparatus namely the bell is operated when the door is opened during passage of the cam 26 beneath the contact 27 and again when the door is closed on the return of the cam 26. Thus it is possible for anyone in the house to tell whether the door has been properly closed or not. In addition and if necessary an ordinary manually operated bell push 28 may be supplied for normal usage.

In order to take the weight of the door more particularly when in the closed position a free rotating or spring loaded pawl 29 may be secured in the framework so that when the door is closed the lower quadrant piece 16 rests upon the said pawl 29. Overlapping cowling 30 may be provided on the top of the door and secured to the frame to provide a weatherproof cover to the apparatus thus preventing entry of rain, dust or the like into the compartments.

As shown the device is in the locked position preventing access from outside to the compartments. When it is desired to place the apparatus in operation the spring finger 19 is withdrawn for example by means of a knurled nut or head 30 and the compartments rotated sufficiently to prevent the finger 19 re-engaging with the recess 21. On delivery of goods the tradesman pulls the door 14 open and this causes the compartments to rotate to expose compartment 8 the tradesman then shuts the door and this automatically causes the spring pawl 18 to engage with the catch above the compartment 9. At the same time when the door 14 was opened and the compartments rotated the spring finger engaged with the non-return recess 20 which permits the compartments to be rotated only in a clockwise direction. On the next delivery of goods the door is operated again in exactly the same manner and this continues until compartment 11 is exposed. In this position the finger 19 engages the locking recess 21 and prevents further rotation of the compartments since all the compartments are now full. Closure of the door 14 automatically locks it against reopening and until a person empties the compartments and resets the apparatus it is locked in the closed position. Suitable access will be provided to the compartments at the rear of the apparatus in the case where the device is built into the wall of a house or other building. The apparatus can, however, be installed on a post for example at the entrance to a gateway in which case it is housed in a com-

partment access to which is reached by a lockable door at the rear of the compartment.

Whilst the invention has been described more specifically in a form in which a number of compartments rotate about a central post or column the compartments may be arranged in the most convenient form for the purpose for which they are intended. Thus, the compartments may be arranged upon an endless belt or chain forming a container of oblong or other shape. Again, it will be apparent that the invention is not limited to a construction in which the compartments rotate in a horizontal plane and these may if desired pursue a vertical or inclined path depending upon the conditions and the purpose for which they are required.

What we claim is:

1. A service cabinet for receiving, storing and delivering goods comprising, in combination, a substantially cylindrical container adapted to be rotatably mounted within an aperture in a wall, door, gate or like structure so that a portion of the container projects on one side of the wall through the aperture, said one side constituting the goods receiving side of the apparatus where goods are deposited in the container, the other side of the wall being that where the goods are withdrawn from the container; a sliding door covering and enclosing the container on said receiving side, and adapted to be moved in one direction to an open position exposing said receiving side; radial partitions in said container dividing the interior thereof into a plurality of compartments; means operatively connecting said sliding door with said container for effecting rotation of the container in said one direction through an angle substantially equal to the angle between two adjacent partitions when said sliding door is moved in said one direction to said open position, said means constituting the sole means for effecting rotation of the container from the receiving side of the apparatus; means for preventing rotation of the container in the opposite direction; and spring operated releasable latch means automatically locking the container against movement in either direction after having been rotated through one revolution by successive openings and closings of the door, said releasable latch means being accessible only from the goods delivery side of the apparatus.

2. A service cabinet for receiving, storing and delivering goods comprising, in combination, a substantially cylindrical container adapted to be mounted for rotation about a vertical axis in a frame positioned within an aperture in a wall, door, gate or like structure, a portion of said container projecting on one side of said frame, said one side constituting the goods receiving side of the apparatus where goods are deposited in said container, the other side of the frame constituting the goods delivering side where goods are removed from the container; an arcuate shaped sliding door mounted for rotation about said vertical axis by means of upper and lower segmental shaped supports and covering and enclosing said container on said receiving side and adapted to be moved in one direction to an open position exposing said receiving side; radial partitions in said container dividing the interior thereof into a plurality of compartments, the lineal distance between the outer edges of any two adjacent partitions being substantially equal to the width of the frame; a latch member on said sliding door adapted to engage in recesses on the container, one recess for each compart-

ment thereof, for effecting positive rotation of the container in said one direction through an angle substantially equal to the angle between two adjacent partitions when said sliding door is moved in said one direction to said open position, said latch member being the sole means for effecting rotation of the container from the receiving side of the apparatus; and a spring-operated releasable latch member positioned on the delivery side of said frame and adapted to automatically engage in further recesses disposed on said container, each corresponding to one compartment thereof, all of said further recesses except one being shaped so that said releasable latch member permits rotation of the container in said one direction and prevents rotation of the container in the opposite direction when engaged therein, said one of said further recesses being adapted to cooperate with said releasable

latch member, said releasable latch member releasably locking the container against movement in either direction, when engaged in said one of said further recesses.
